UNITED STATES PATENT OFFICE.

VERNON J. HARRIS, OF ADRIAN, MICHIGAN.

VALVE-TAPPET-SILENCING MECHANISM.

1,425,766.

Specification of Letters Patent. Patented Aug. 15, 1922.

Continuation of application Serial No. 439,159, filed January 22, 1921. This application filed July 12, 1922. Serial No. 574,350.

To all whom it may concern:

Be it known that I, VERNON J. HARRIS, a citizen of the United States, residing at Adrian, county of Lenawee, State of Michigan, have invented a certain new and useful Improvement in Valve-Tappet-Silencing Mechanism; and declare the following to be a full, clear, and exact description of the same, such as will enable others skilled 5 in the art to which it pertains to make and use the same, reference being had to the accompanying drawings, which form a part of this specification.

My invention relates to valve tappet silencers and reference is hereby made to my co-pending application Serial No. 439,159, filed January 22, 1921. In the form of construction standardized in the Chevrolet motor there is provided an aligner or guide lock which connects the adjacent ends of the two axially aligned sections of the valve push rod, or as otherwise also termed, the valve push rod and the push rod plunger. In operation this aligner has a tendency to 25 wobble or oscillate about its vertical axis and knock against the adjacent rigid side wall of the engine casing, producing a disagreeable clacking noise. Noise may also be produced by the vertical movement of the 30 aligner within the provided retaining grooves formed in the push rod sections in which the aligner is mounted. Furthermore, a slight oscillatory rotation of the plunger about its longitudinal axis results 35 from this wobbling action of the aligner. This tendency to oscillate increases with the wear of moving parts and produces inaccuracy in the valve timing in that the push rod plunger is not struck squarely each time by 40 the revolving cam.

My improved silencer is so formed as to be easily, quickly and releasably engaged with the valve push rod without any change in the adjustment thereof or of its adjusting 45 nuts so as to be carried by such push rod, and is adapted to yieldingly engage the aligner or guide lock, exerting pressure thereon to prevent rattling of the aligner against the adjacent rigid side of the engine 50 casing or within the provided grooves in which the aligner is mounted. This silencer when in position also serves to maintain

the plunger and push rod in alignment so that the end of the plunger will be struck squarely by the revolving cam. 55

In the drawings,

Figure 1 is an end view of an internal combustion engine partly broken away to show the operation of the valve push rod.

Fig. 2 is a section taken on line 2-2 of Fig. 1.

Fig. 3 is a section taken on line 3-3 of Fig. 1.

Fig. 4 is a front elevation of my device.

Fig. 5 is a side elevation of my device. 65
Let *a* indicate the engine casing and *b* the cam shaft provided with the cam *c*. The push rod is indicated as *d* and its lower section or what is more commonly termed the plunger, as *e*. Threaded on the lower end 70 of the push rod is a nut or collar *f* which contacts with the adjacent end of the plunger and by virtue of the adjustment of which on the push rod the length of the rod is regulated. This nut *f* is adjustably locked by 75 means of a lock nut *g* threaded on the plunger above such nut.

To fasten the plunger *e* and push rod *f* together to reciprocate as one piece, there is provided a pressed metal guide lock or 80 aligner *h* turned inwardly on opposite sides forming wings which seat in vertically-disposed registering slots formed in the nut *f* and the plunger *e*, one on each side thereof, and by virtue of the lateral extension of 85 such side wings rotation of the plunger and push rod relative the engine casing is limited.

It is apparent that there is clearance between the aligner and engine casing and that this clearance will permit a limited oscillatory rotation of the aligner causing it to strike the engine casing wall, and this noise would increase in direct proportion to the increase and permitted play due to wear 90 of the moving parts.

The lower end of the plunger is beveled to a diameter which should be struck squarely by the revolving cam and this permitted rotatable oscillation of the plunger causes 100 the cam to strike the plunger unevenly. This action also increases with the wear of the moving parts and in time the lower end of the plunger is so worn as to prevent ac-

curate operation of the timing mechanism. The above construction is standard on the Chevrolet engine.

My silencer comprises a resilient spring member *i* having a body portion *i*' so formed as to be releasably sprung about the push rod and yieldingly, grippingly, straddling said push rod to be carried thereby. This body portion is provided with a pair of spaced-apart downwardly-extending prongs or forks, curved or undulated as shown in Fig. 5, one on each side of the plunger and extending longitudinally thereof and interposed between the aligner and the engine 10 casing. These prongs exert yielding pressure on said aligner and engine casing and prevent rattling of the aligner against the casing. It also maintains the plunger in alignment with the push rod and prevents 15 relative rotation thereof about its vertical axis.

It will be seen that this silencer may be easily and quickly attached to the push rod without unscrewing the adjusting nuts and 20 otherwise interfering with the timing adjustment of the valve operating mechanism such as would be the case were the silencer held between the lock nut and adjusting nut on the push rod.

30 What I claim is:

1. In a device of the class described, in combination, a valve push rod, the co-operating cam actuated plunger, a guide lock connecting said plunger and push rod together, a spring guide member shaped so as to partially encircle the push rod resiliently gripping the same so as to be carried thereby, such spring guide member provided with a pair of downwardly extending 35 prongs positioned one on each side of the plunger, interposed between the guide lock member and the engine casing, said prongs so shaped as to exert yielding pressure on said guide lock to prevent its striking 40 against the engine casing.

2. In a device of the class described, in combination, a valve push rod, a co-operating plunger, said push rod and plunger each provided with longitudinal extending registering slots, a guide lock adapted to be received in said slots connecting said push rod and plunger together, a guide spring shaped so as to be sprung about such push rod gripping the same in such a manner as 50 to be carried thereby, said spring provided with a pair of prongs extending downwardly one on each side of the push rod interposed between the guide lock and engine casing each of said prongs curved so as to hold 55 the guide lock outwardly from said engine casing and adapted to maintain the alignment of said push rod and plunger.

3. In a device of the class described, in combination, a valve push rod, a co-operating cam actuated plunger, a guide lock con-

necting said plunger and push rod, a guide spring provided with a body portion adapted to resiliently grip the push rod to be carried thereby and provided with a pair of extensions disposed on opposite sides of the 70 push rod extending longitudinally thereof shaped so as to exert pressure on said guide lock in such a manner as to prevent its rotation relative the axis of the push rod.

4. In a device of the class described, in 75 combination, a valve push rod, a co-operating cam actuated plunger, a rotating cam, means connecting said plunger and push rod, a spring guide member adapted to exert yielding pressure on said connecting means 80 so as to thereby hold the face of the said plunger in alignment with the cam, said spring guide provided with a body portion shaped so as to grip the push rod in such a manner as to be carried thereby, being held 85 thereon by virtue of the spring pressure in said body portion.

5. The combination with an engine casing, a valve push rod, an actuating member and a guide lock connecting the proximate ends of said push rod and actuating member together, of a device of the class described, comprising resilient undulated guide lock engaging prongs disposed between said guide lock and said engine casing, and connected by a body portion adapted 95 to be engaged with the push rod.

6. The combination with an engine casing, a valve push rod, a plunger adapted to actuate said push rod and a guide lock adapted to hold the proximate ends of said plunger and push rod together, of a silencer comprising a body portion adapted to be engaged with the push rod so as to be carried thereby, said body portion provided with 100 resilient undulated guide lock engaging portions adapted to be interposed between the guide lock and engine casing and extending substantially longitudinally the push rod on opposite sides thereof and adapted by virtue of their undulated construction to exert spring pressure on said guide lock.

7. The combination with a valve push rod, an actuating member and a guide lock connecting said push rod and actuating member 115 together, of a silencer shaped to resiliently embrace said push rod to be carried thereby and adapted to exert yielding pressure on said guide lock to prevent its rotation.

8. The combination with an engine casing, a valve push rod, an actuating member and a guide lock engaging adjacent ends of said push rod and actuating member together of a silencer having a body portion shaped so as to resiliently embrace said push 120 rod in such a manner as to be carried thereby and adapted to frictionally engage said engine casing and exert outward yielding pressure on said guide lock.

9. The combination with an engine cas- 130

ing, a valve push rod, an actuating member and a guide lock connecting adjacent ends of said push rod and actuating member together of a spring guide member shaped so as to resiliently embrace said push rod so as to be carried thereby and provided with guide lock engaging portions adapted to

slidably frictionally engage said engine casting and exerting yielding outward pressure on said coupling member. 10

In testimony whereof, I sign this specification.

VERNON J. HARRIS,
